UNITED STATES PATENT OFFICE

166,437

HOLDER FOR AN HARMONICA AND AMPLIFIER PICKUP THEREFOR

Edward A. Zielinski, Berwyn, Ill., assignor of one-half to Joseph S. Kishel, Brookfield, Ill.

Application July 25, 1951, Serial No. 16,010

Term of patent 14 years

(Cl. D56—1)

To all whom it may concern:

Be it known that I, Edward A. Zielinski, a citizen of the United States, residing at Berwyn, in the county of Cook and State of Illinois, have invented a new, original, and ornamental Design for a Holder for an Harmonica and Amplifier Pickup Therefor, of which the following is a specification, reference being made to the accompanying drawing, forming a part hereof.

In the drawing:

Fig. 1 is a perspective view of a holder for an harmonica and amplifier pickup therefor;

Fig. 2 is a side elevational view of the holder shown in Fig. 1;

Fig. 3 is a top plan view of a holder embodying my new design; and

Fig. 4 is an end elevational view thereof.

The bottom of the holder, as seen in the drawing, is plain.

I claim:

The ornamental design for a holder for an harmonica and amplifier pickup therefor, substantially as shown and described.

EDWARD A. ZIELINSKI.
